UNITED STATES PATENT OFFICE.

FRED SUCCIE, OF BREWER, MAINE.

GUIDE-FLANGE FOR PAPER-ROLLING MACHINES.

SPECIFICATION forming part of Letters Patent No. 687,443, dated November 26, 1901.

Application filed February 1, 1901. Serial No. 45,555. (No model.)

To all whom it may concern:

Be it known that I, FRED SUCCIE, a citizen of the United States, residing at Brewer, in the county of Penobscot and State of Maine, have invented certain new and useful Improvements in Guide-Flanges for Paper-Rolling Machines; and I do hereby declare the following to be a full, clear, and exact description of the invention, such as will enable others skilled in the art to which it appertains to make and use the same.

My invention consists of improved guide-flanges for paper-rolling machinery, and is fully illustrated in the accompanying drawings, in which—

Figure 1 is an isometric view of complete device mounted on a shaft. Fig. 2 is a side elevation of shaft, showing tapering screws and ends of lessened diameter. Fig. 3 is an enlarged side elevation of guide-flange. Fig. 4 is an enlarged side elevation of screw-clamp. Fig. 5 is an enlarged longitudinal section of screw-clamp. Fig. 6 is a side elevation of hollow core. Fig. 7 is an enlarged bottom view of guide-flange.

Similar letters refer to corresponding parts throughout the figures.

In the manufacture of pulp and paper the sheet as it comes from the machine is wound upon a hollow core mounted upon a revolving shaft, and in this process there is generally a tendency toward uneven winding, which produces a roll having one end concaved and the other convexed instead of flat, a result which destroys the symmetrical form of the finished roll and makes packing and handling inconvenient and difficult. To remedy this difficulty, various devices are employed, and mine is described as follows:

The shaft A is formed with smooth spindles $a a'$ of lessened diameter at each end adjacent to its bearings B B to permit the fitting on of the guide-flanges C C, as hereinafter explained, and from points at or near its center is threaded with right and left hand screws $a' a'$, extending, respectively, to said spindles and tapering at their outer ends to the diameters of said spindles. A removable hollow core D, of a length about equal to the width of the sheets to be wound, having a bore of greater diameter than said shaft, is shipped upon the shaft near its mid-length and is rig-

idly clamped to the shaft and prevented from both rotary and longitudinal motion thereon by the screw-clamps E E, which consist of 55 nuts working on the threaded portions of the shaft and having forwardly-projecting conical longitudinally-flanged extensions $e e'$, which extensions enter each end of the core and as the nuts are screwed toward the middle of the shaft by means of a wrench bear upon the inner surface of the core, the sharp flanges of the extensions cutting into the core sufficiently to hold it rigidly to the clamp and through the clamp to the shaft. 65

Two guide-flanges C C are used, and each is constructed in the following manner: The flange proper, c, consists of an annular thin stiff disk, preferably of metal, having a bore sufficiently large to pass over the end of the 70 core and having a jaw c' large enough to admit the screw-threaded portion of the shaft into the bore. The flange proper, c, is rigidly connected by a sufficient number of arms with a split nut c'' , formed to engage with the 75 threading on the shaft and having a split or jaw c''' sufficiently large to admit the spindle a of the shaft into the bore of the nut, but not large enough to admit the threaded portion a' of the shaft. The flange c and nut c'' 80 may be formed integral, if desired. The rims of the clamps E E may be widened and screw-threaded, and the split nut c'' may be formed to work and turn upon said rims instead of upon the shaft, if such construction be preferred.

The disks c may be made of any desired diameter; but if in the process of winding one should be broken or a larger flange be required the nut c'' may be slightly turned back 90 and a new or larger disk of the same pattern, but not connected with a nut, may be inserted between the original disk and the end of the roll and the nut again turned forward till the new disk bears upon the end of the 95 roll. The object of the diminished size of the ends of the shaft is to allow a smaller jaw in nut c'' , so that when the guide-flange is screwed toward the center of the shaft it cannot fall off the shaft when it is inverted 100 and the jaw comes uppermost.

In operation the core is placed upon the shaft and clamped thereto by the clamps E E, as before described. The winding is then be-

gun, and as the roll begins to attain moderate size the guide-flanges are adjusted by hand without stoppage of the shaft, the split in the nut permitting the entrance of the 5 spindle end of the shaft into the bore of the nut and the jaw in the disk permitting the entrance of the threaded shaft into the bore of the disk. The guide-flange with its nut is then gently impelled toward the roll, when 10 the tapering end of the threaded portion of the shaft enters the bore of the nut and engages with its interior threading, and the whole guide-flange being held by the hand at α or elsewhere and prevented from turning with the shaft is immediately screwed 15 forward until the flange bears on the roll.

Any convenient method of clamping the core to the shaft may be adopted; but I prefer that above described—viz., the use of the 20 screw-clamps E E.

Having thus described my invention, what I claim, and desire to secure by Letters Patent, is—

1. In a paper-rolling machine and in combination with a winder-shaft having a screw-threaded portion intermediate its ends, and a 25 spindle end of diminished diameter, and with a hollow core rigidly clamped to the central portion of said shaft, the herein-described 30 guide-flange consisting of an annular disk and a split nut rigidly connected thereto and concentric therewith, said disk having a bore sufficiently large to receive said core and a jaw sufficiently large to admit the shaft of

the winder into said bore, and said nut being 35 internally threaded to engage with the winder-shaft and turn thereon and having a split or jaw sufficiently large to admit the diminished end of the winder-shaft into its bore.

2. In a paper-rolling machine the combination 40 of a winder-shaft screw-threaded with a right-hand screw from at, or near, its center toward one of its ends and with a left-hand screw from at, or near, its center toward its other end, both ends of the shaft between 45 its bearings and its screw-threadings being smooth spindles of diminished diameter; a hollow core having a bore of greater diameter than said shaft; a pair of screw-clamps each being adapted to engage with 50 the screw-threading on said shaft and having a forwardly-extending, longitudinally-flanged conical projection adapted to enter the bore of said core; and a pair of guide-flanges each consisting of an annular disk 55 having a bore sufficiently large to receive said core and a jaw sufficiently large to admit said shaft into its bore and being rigidly connected to, or formed integral with, a split nut threaded to engage with said shaft and turn forward thereon and having a split or jaw sufficiently large to admit the diminished end of said shaft into its bore.

FRED SUCCIE.
